UNITED STATES PATENT OFFICE.

WARD L. BUMGARDNER, OF COLUMBUS, OHIO.

RETURN ENVELOPE.

Application filed January 4, 1924. Serial No. 684,332.

To all whom it may concern:

Be it known that I, WARD L. BUMGARDNER, a citizen of the United States of America, residing at Columbus, in the county of 5 Franklin and State of Ohio, have invented certain new and useful Improvements in Return Envelopes, of which the following is a specification.

My present invention relates generally to 10 that class of envelopes designed to provide for the ready return of the original envelope by the original addressee to the original addressor and my invention further and especially aims toward the provision of a return 15 envelope designed for the original mailing of small articles of merchandise, which will enable the addressee to re-mail the envelope with minimum trouble and minimum expenditure of time and a still further object 20 is the provision of an envelope of this nature, the manner of manipulation of which for remailing purposes will be plain and easy of accomplishment without necessitating lengthy and complicated directions as regards folding or re-folding.

In the accompanying drawing which illustrates my present invention and forms a part of this specification,

Figure 1 is a front view of a portion of the 30 envelope embodying my invention and showing the closing flap in detachable connection with the body of the envelope as in original mailing,

Figure 2 is a similar view showing the 35 flap sealed in closed position with the original mailing extension removed,

Figure 3 is a cross sectional view taken 40 through the envelope substantially on the line 3—3 of Figure 1,

Figure 4 is a vertical sectional view taken centrally through a portion of the envelope showing the flap as originally constituted, in released position,

Figure 5 is a vertical sectional view 45 through the complete envelope taken substantially on line 5—5 of Figure 1,

Figure 6 is a view similar to Figure 4 with the original mail extension removed from the flap preparatory to re-mailing, and

50 Figure 7 is a vertical sectional view taken substantially on line 7—7 of Figure 2.

Referring now to these figures my invention proposes an envelope of the character first above set forth, the body 10 of which is 55 formed with horizontally overlapping por-

tions 11 and 12 at the front thereof as seen particularly by a comparison of Figures 3 and 5, the portion 12 being sealed upon the outer surface of the portion 11 for part of the length of the envelope and having its remaining portion free adjacent to the open end of the envelope and provided with a longitudinal slit 13 spaced from and parallel with its free edge to form a tongue 14 extending toward the open end of the envelope and located adjacent thereto. This tongue 14 has a cross slit 15 whose angular ends 16 in the disposition shown particularly in Figure 2 thus form a lip 17 projecting away from the open end of the envelope. 70

The body 10 of the envelope also has a flap 18 bendable over its open end to close the latter and foldable for this purpose with the front of the envelope, the flap extending entirely from one side of the envelope to 75 the other and being provided with a gummed inner surface 19 and an outer surface forming an address receiving space for the name and address 20 of the addressor in the original mailing adapted also to constitute the 80 addressee when the envelope is re-mailed.

The flap 18 is also provided beyond its gummed and address receiving portion with an extension 21, detachable from the flap itself by virtue of a perforate line 22 between the flap and its extension, said extension extending from one side of the flap to the other and forming upon its outer surface an address receiving space for the name and address of the addressee in the original mailing, indicated at 23 in Figure 1. 85

The flap 21 is also provided with a slot 24 paralleling and adjacent to its free end and located centrally between its sides, so as to receive therethrough the tongue 14 in the 90 manner shown in Figures 1 and 5 in the original mailing of the envelope.

It is thus obvious that the envelope may in view of the detachable connection between its flap extension 21 and the body of the 100 envelope in the original mailing be utilized to transmit small articles of merchandise, the envelope being at this time unsealed. After the articles are placed within the envelope the flap 18 with its extension 21 is folded flatwise against the front of the envelope after lifting the tongue 14 so that the flap and its extension are disposed beneath the tongue, the latter being then bent and thrust inwardly and outwardly through 105 110

the slot 24 of the flap extension 21 as shown in Figure 5 until the lip 17 of tongue 14 is upwardly and inwardly beyond the slot 24 so that it may spring across the slot at 5 the inner face of the flap extension as shown in Figure 5 so as to thus prevent accidental withdrawal of the tongue 14. In this way the flap and its extension are detachably held, that is without sealing the envelope 10 so that the merchandise is free of passage under the postal regulations, to the addressee whose name appears upon the flap extension 21. Upon receipt by the addressee it is simply necessary for the latter, in order 15 to re-mail the envelope, for instance with a remittance enclosed to cover the cost of the merchandise, to withdraw the tongue 14, remove the contents from the envelope, place such matter within the envelope as it is desired to forward to the original addressor and then remove the flap extension 21 by 20 detaching the same along the perforate line 22 and, after pressing the tongue 14 flatwise beneath the flap 18, sealing the latter in closed position by virtue of its gummed inner surface 19.

It is obvious that upon removal of the flap extension 21 all reference to the original addressee is removed, there remaining upon 30 the envelope merely the name and address of the original addressor with the contents of the envelope such that it readily passes under the postal regulations in a sealed condition.

35 I claim:

1. A return envelope of the character described having a body provided with horizontally overlapping portions and open at one end, said overlapping portions being 40 permanently connected for a portion of the length of the envelope and the outer overlapping portion having a free tongue adj-

acent to and projecting toward the said open end and provided with a cross slot having angular ends forming a lip projecting away from the open end of the envelope, said envelope body having a flap foldable over the open end thereof and upon the front of the envelope and provided with an extension detachable therefrom and having a slot through which the said tongue may be extended, the lip of the said tongue being adapted to extend across the said slot of the extension in the connected position to prevent accidental withdrawal of the tongue. 55

2. A return envelope of the character described having a body provided with horizontally overlapping portions and open at one end, said overlapping portions being permanently connected for a portion of the length of the envelope and the outer overlapping portion having a free tongue adjacent to and projecting toward the said open end and provided with a cross slot having angular ends forming a lip projecting away from the open end of the envelope, said envelope body having a flap foldable over the open end thereof and upon the front of the envelope and provided with an extension detachable therefrom and having a slot through which the said tongue may be extended, the lip of the said tongue being adapted to extend across the said slot of the extension in the connected position to prevent accidental withdrawal of the tongue, 70 75 said flap and its said extension having address receiving spaces upon their outer surfaces and said flap having an inner gummed surface whereby it may be sealed across the front of the envelope after detachment of the said extension therefrom.

In testimony whereof I have affixed my signature.

WARD L. BUMGARDNER.
